UNITED STATES PATENT OFFICE

143,326

DESIGN FOR A RAZOR HANDLE

Herman H. Kempf, Garden City, N. Y.

Application May 29, 1945, Serial No. 119,797

Term of patent 14 years

(Cl. D22—3)

To all whom it may concern:

Be it known that I, Herman H. Kempf, a citizen of the United States residing at Garden City, Long Island, county of Nassau, and State of New York, have invented a new, original, and ornamental Design for a Razor Handle, of which the following is a specification, reference being had to the accompanying drawing forming part thereof.

Fig. 1 is a perspective view taken from the rear of a razor handle embodying my new design.

Fig. 2 is a similar view taken from the front.

I claim:

The ornamental design for a razor handle, as shown.

HERMAN H. KEMPF.
